IMPROVED MACHINE FOR FILING SAW-TEETH.

M. M. PETTES, OF OXFORD, MASSACHUSETTS.

Letters Patent No. 60,237, dated December 4, 1866.

SPECIFICATION

TO ALL WHOM IT MAY CONCERN:

Be it known that I, M. M. PETTES, of Oxford, in the county of Worcester, and State of Massachusetts, have invented a new and improved Guide to be used in the Filing of Saw-Teeth; and I do hereby declare that the following is a full, clear, and exact description thereof, which will enable others skilled in the art to make and use the same, reference being had to the accompanying drawings forming part of this specification.

The present invention relates to a new and useful implement or device, to be used for the filing of the teeth of saw-blades, and it consists in so arranging or hanging a guide for the file used upon a yoke or frame of suitable shape, to be fitted over the toothed edge of the saw-blade and moved along and upon the same, as to be susceptible of such adjustments, with regard to the length of the saw-blade, as may be necessary to produce the desired form, shape, size, or style of teeth thereon, whether the teeth are to have more or less pitch, or to be more or less beveling, or "fleming," so called, or whether they are to be filed deeper upon one side of the blade than upon the other, as will be obvious from the following detail description thereof, reference being had to the accompanying plate of drawings, in which—

Figure 1 is a plan or top view of my improved guide, showing it as applied to a saw-blade.

Figure 2, a side elevation of the guide and the saw-blade.

Figure 3, a side view of a holder for the file, which holder and its file in

Figure 4 are shown in transverse section.

Figure 5, a view of a file in the direction of its length, which is particularly designed for use in my improved guide for the filing of saw-teeth; and

Figure 6, a transverse section of the file, shown in fig. 5, taken in the plane of the line xx of the same figure.

Similar letters of reference indicate like parts.

A in the drawings represents a guide, which is made of an angular shape, as shown in figs. 1 and 2 of the drawings, or, in other words, suitable for being used as a guide or way for the three-cornered files ordinarily used in the filing of saw-blades. This guide A is cut out upon each side at B, and at C is hung or swivelled to the upper surface of the straight side or edge D of the semicircular-shaped frame E, across which frame the guide extends; its point of hanging to the side D being the centre of the arc or circle of its semicircular side G. The edge of the semicircular side G is provided with a series of notches or teeth $a a$, at equal distances apart, corresponding to which notches or teeth graduations are made upon the upper face of the circular bar G, as plainly shown in the drawings, which may or may not be numbered or otherwise properly marked from the centre division or graduation in a direction toward each end of the bar, for a purpose to be hereinafter explained. Over the notched edge of the circular bar G, a slide, H, is placed, through an aperture in which slide screws the set-screw I of the arm M, projecting from and attached to the under side of the guide A; this arm M having another set-screw N below its screw I, which is in proper position for being set in any one of the series of circular-shaped cavities, depressions, or notches e , made in the face of the under-projecting or extension portion, o , of the slide H. At each end, P, of the circular frame E, is a short trunnion pin, Q, by means of which the frame is hung in the uprights R of a yoke frame S, which yoke is made of suitable shape for being placed over the toothed edge of a saw-blade, extending down upon each side of the same, where, by means of side set-screws T, at suitable points of its length, it is secured to the saw-blade with sufficient tightness to hold it firmly thereon, while at the same time it can be moved or slid with ease forward or backward upon the saw-blade. The central portion U of the yoke frame S, upon its upper side or edge, is cut out so as to expose the edge of the saw, this cut-out portion of the yoke being of sufficient length to expose the saw-blade to the action of the file used, even if the guide for the file is set at the most extreme points or ends of the circular bars. V, set-screws, one in each end of the circular frame E, which set-screws bear upon and against the upper side of the yoke-frame S, so that according as they are screwed into or out of the frame E, they will either raise from or lower the said frame to the yoke; the uprights in which the frame E by its trunnion-pins is hung being suitably formed to allow of its adjustment, as above explained. By the trunnion-pins, the circular frame can be swung in the bearings of the uprights, and thus brought to any plane of inclination with regard thereto, where, by properly adjusting the set-screws W, one upon each of its sides, it can be securely fastened and held in position.

Having thus described the arrangement of my improved guide for the files used in the filing of saw-teeth, I will now explain the manner in which it is used upon saws, the blades of which are straight. The saw-blade

is first secured in a clamp X, as is now done when saws are to be filed, and then this clamp fastened in any suitable vise, when the yoke of the implement is placed over the toothed edge of the saw-blade, resting by its lower edge upon the clamp X at such portion of the same that when the guide is properly adjusted, as will be explained, it will be in position for some one of the several teeth of the saw, according to the one at which it is intended to commence the filing operation, when, the guide being then adjusted in position by means of its several set-screws to correspond with the form, size, style, or shape of tooth which the saw-blade is to have, the teeth can be then filed by running through the guide the file which is used therefor, and moving the yoke to and on which the guide is hung and arranged, as described, in the proper direction upon the saw-blade to bring the guide in position for each and all the teeth of the saw-blade in regular order and succession; the sliding of the yoke being gauged by means of a spring-pawl Y hung upon the yoke frame, in proper position for engaging with each successive tooth of the saw-blade after it has been filed, thereby producing a uniformity in the distance between each tooth, as they are severally gauged by the tooth next preceding, an advantage of the utmost importance. By the arrangement of the guide for the file herein above explained, it is plain to be seen that, loosening the set-screw I, the guide can be swung around and upon the circular frame to which it is hung, either to the right or left, and thus brought to any desired angle with regard to the length of the saw-blade, according to the bevel or "fleming," so called, which the teeth are to have, when, by engaging such screw I with the notch of the curved bar corresponding therewith, the guide is secured in such position that if then the set-screw N be loosened or disengaged from the notches e, the guide can be swung upon the circular frame, so as to incline its sides either more or less according to the pitch of tooth desired, where it can be secured by then setting the said screw N in the proper notch of the series of notches e, the depth of tooth being regulated by properly adjusting the set-screws V to raise or lower the frame E from or to the yoke, and the guide also adjusted for the filing of a tooth deeper upon one side of the blade than the other by tilting the frame E in the proper direction through the set-screws W. In order to enable the spring-pawl Y to be regulated in position upon the yoke frame, according to the position which the guide occupies, the pawl is hung to a slotted bar, Z, that by means of a set-screw A² is secured to the yoke frame; the manner of adjustment of the pawl Y being plainly apparent, without any further explanation, by an inspection of the drawings.

From the above description of my improved device or implement to be applied to saw-blades, the teeth of which are to be filed, it is obvious that the filing of the teeth can be accomplished with the utmost uniformity and accuracy throughout the whole length of the saw-blade, and with great rapidity, ease, and convenience; an implement, by my invention, being produced, which has long been desired, and which will prove of great benefit and utility.

In figs. 3 and 4, a holder for the three-cornered file is shown, by means of which the file can be used with greater convenience and ease in the guide A. This holder consists of a suitable shaped frame, B², to receive the file, and leave one corner or angle and the two sides forming the same exposed for the whole length of the file, and a handle, C²; the file being secured in the said holder by means of a set-screw, D², or in any other proper manner, and prevented, by means of the ferrules E² at each end of the holder, from acting upon the surfaces or sides of the guides A, over which it passes, as it is moved forward and backward through the same. In lieu of using a holder for the file, the file may be used as heretofore, it being only necessary that at each end of the file suitable ferrules should be secured to it to prevent it from acting upon the sides and surfaces of the guide; or that the file should be formed at each end with smooth pieces F², the surfaces of which project beyond the teeth of the file, as plainly shown in figs. 5 and 6, which form of file is especially adapted for use in my improved guide, and on which I reserve to myself the right to make hereafter separate application for Letters Patent; this file, between the two smooth ends, being also made straight in lieu of bulging or concave, as has heretofore been the case. The form of guide A may be varied in many respects, according to the shape of the file used, and it may be provided with friction-rollers if so desired, and therefore I do not intend to limit myself to any one particular form or manner of constructing the same; and furthermore, in lieu of hanging the guide so that it can be susceptible of two movements herein described, viz, being brought to any desired angle with regard to the length of the saw-blade, and its sides so inclined as to be adapted to any pitch of teeth, it may be so arranged or hung upon its frame as to be susceptible of only one of said movements, according to which may be the most desirable, but I deem it best to hang it as explained, because its utility and adaptability to all the requirements are thereby much increased. And furthermore, the guide may be hung directly to the yoke frame, instead of through the circular frame; but in such a case the adjustment of the guide to any depth of tooth, as well as to the filing of a tooth deeper upon one side of the saw-blade than the other, could not be obtained.

It may be here remarked, in conclusion, that by simply providing the yoke frame with an arm susceptible of being increased or decreased in length, my improved file guide can be adapted to circular saw-blades as well as straight blades, as has been herein particularly described; the yoke frame, when used upon circular saws, being hung by its arm so as to swing upon the centre arbor of the saw.

I claim as new, and desire to secure by Letters Patent—

1. So hanging the guide A, or its equivalent, to and upon any frame or holder suitable for being secured upon a saw-blade, that said guide can be adjusted to various angles with regard to the length of the blade, substantially as herein described and for the purpose specified.

2. So hanging the guide A, or its equivalent, to and upon any frame or holder suitable for being secured upon a saw-blade, that the said guide can be adjusted in position to vary the pitch of the teeth of the saw-blade, substantially as described.

3. So hanging the guide A, or its equivalent, to and upon any frame or holder suitable for being secured upon a saw-blade, that it can be adjusted both to various positions or angles, with regard to the length of the

blade, and also to accommodate it to various pitches of the teeth of the saw, substantially as and for the purpose described.

4. So hanging the frame E, or its equivalent, to which a guide, A, or its equivalent, is secured in any proper manner, to a yoke or other frame, suitable for being secured upon a saw-blade, that it can be either raised or lowered, or so set as to more or less incline the said guide A, or both, substantially as herein described and for the purposes specified.

5. The guide A, frame E, with circular bar G, and yoke S, when arranged, combined, and connected together, so as to be susceptible of each and all the several adjustments herein above described, and substantially as and for the purposes specified.

6. In combination with the above, I claim the spring-pawl Y, when arranged upon the yoke frame S, or its equivalent, so as to operate substantially as and for the purpose described.

The above specification of my invention signed by me this   day of May, 1866.

M. M. PETTES.
